US0D1036475S

(12) **United States Design Patent** (10) Patent No.: **US D1,036,475 S**
(45) Date of Patent: ** Jul. 23, 2024

(54) **DISPLAY SCREEN OR PORTION THEREOF WITH GRAPHICAL USER INTERFACE**

(71) Applicant: **HUAWEI TECHNOLOGIES CO., LTD.**, Guangdong (CN)

(72) Inventors: **Chao Liang**, Shanghai (CN); **Ping Song**, Shenzhen (CN); **Anqi Liu**, Shenzhen (CN); **Xinxin Lan**, Shenzhen (CN)

(73) Assignee: **HUAWEI TECHNOLOGIES CO., LTD.**, Shenzhen (CN)

(**) Term: **15 Years**

(21) Appl. No.: **29/922,178**

(22) Filed: **Dec. 21, 2023**

Related U.S. Application Data

(62) Division of application No. 29/801,705, filed on Jul. 30, 2021.

(30) **Foreign Application Priority Data**

Feb. 1, 2021 (CN) 202130073144.0

(51) **LOC (14) Cl.** **14-04**

CLAIM

The ornamental design for a display screen or portion thereof with graphical user interface, as shown and described.

DESCRIPTION

The single FIGURE is a front view of a display screen or portion thereof with graphical user interface showing our new design.

The dash-dot lines in the drawing show a display screen or portion thereof and forms no part of the claimed design.

1 Claim, 1 Drawing Sheet
